UNITED STATES PATENT OFFICE.

WILLIAM KLEITZ, OF ALBANY, NEW YORK.

CONCRETE-MOLDING APPARATUS.

Application filed September 3, 1927. Serial No. 217,324

This invention relates to concrete forms and more particularly to forms for producing hollow concrete floors or ceilings.

An object of the invention is to provide 5 new, simple, and efficient apparatus for molding hollow concrete floors.

Other features and objects of the invention will become apparent by reference to the following detailed description and accompanying drawings in which,

Fig. 1 shows an end view and partial isometric perspective of the form and floor in three stages of erection and completion, and

Fig. 2 shows a modified arrangement of 15 the forms.

Referring now to the drawings, 10 indicates the vertical supports which may be of either wood or metal, the dimensions and spacing of which may be proportioned according to the loads to be carried thereby.

A horizontal support of the material similar to supports 10 is indicated at 11. In order that the concrete may be poured in such a manner as to produce hollow flooring, use is 25 made of a pair of forms, one of which is indicated at 12. Such form is preferably of metal of a gage heavy enough to withstand the pressure of the concrete. It may be of any size and length desired for the purpose 30 in view. As shown in the drawings, the top of the form 12 is provided with a flange 13 while the bottom thereof is also provided with a flange 14 the purpose of which will hereinafter be explained in detail. That portion of form 12 indicated by the expanse A 35 may be continuous, i. e. formed as an integral part of the form as shown in Fig. 1 or may be composed of separable portions as indicated in Fig. 2. By such a separation of

40 that portion of the form at any point or points the space indicated at B can be reduced to a comparatively narrow width resulting in a narrower piece of form indicated at 30, such piece of form being described in detail hereinafter. Moreover this arrangement will result in additional strength for the completed structure. Use is also made 45 of a second form 15 similar in shape to form 12, being provided with a flange 16 and an upturned flange 17. In practice the forms 50 12 and 15 are so positioned that their lower edges overlap whereby the flange 14 rests against the upper face of the bottom extension of form 15 while the flange 17 rests 55 against the underside of the bottom surface of form 12. These flanges serve the purpose

of strengthening the edges of the forms and also the further purpose of providing a good joint when the forms are assembled for use. In order that the forms so assembled may 60 be spaced from the flooring, use is made of metal saddles 18 of triangular shape and also metal saddles 19 partially supported by reinforcing bars 20 as shown. Use is also made of the usual wire mesh reinforcing 21, 65 such reinforcing being adapted to remain permanently in the concrete to add strength thereto.

In order that the forms when assembled may be held in spaced relation to each other, 70 use is made of spreaders 22 of wood or metal, such spreaders being adapted to fit inside of the form and to hold it in shape against the pressure of the concrete. Such spreaders may be spaced at any desired intervals along 75 the length of the forms. Use is also made of reinforcing rods 25 to aid in the strengthening of the concrete and also to further aid in the complete formation of a hollow space 80 in the concrete floor. A detailed description 85 of the use of these rods is included hereafter.

Having explained and described the essential parts of the invention, the operation is as follows. The saddles 18 and 19 together with the reinforcing rods 20 and the wire 90 mesh 21 are positioned as shown in the drawings. The forms 12 and 15 are next placed in position whereby the lower edges thereof overlap each other. In such position the forms are properly spaced by means of the 95 spreaders 22 and are held in such spaced relation by means of suitable wire binding therearound. With the forms in place the reinforcing rods 25 are positioned as shown in the drawings, that is, with their ends upturned 100 to conform to the shape of the form. Concrete may then be poured to a height approximately level with the top of the form. After the concrete so poured has become sufficiently hardened, the forms 12 and 15 may 105 be removed by first removing the spreaders 22 and then withdrawing first the form 12 and then the form 15. At this time it is well to note that the tapered shape of the members comprising the form will permit their ready 110 withdrawal from the void so formed in the concrete. Moreover to permit the ready removing of each half of the form members, three dimensions must be in proper relation to each other. The dimension A must be less than dimensions B and C and the dimension C must not be more than that indicated at B.

After the forms have been removed, an additional piece of form indicated at 30 is spaced within the void formed by the upturned edges of forms 12 and 15. Form 30 may be of any material desired but is preferably of wood or some other inexpensive material since it remains permanently in the structure. In order that this form may be securely fastened in such a manner that the top edges thereof 10 rest against the bottom edges of the previously poured concrete, the reinforcing rods 25 are bent over the void formed by the upturned edges of forms 12 and 15 and these rods or any other suitable reinforcement 15 crossing the void are secured together by any means to develop the full strength of the same as continuous members, after which the form 30 is secured to such joined rods in any desired manner, such as by wire tying. With 20 this form in place the void may now be filled with concrete and the finishing surface of a finer material applied immediately thereafter.

While the preferred form has been illustrated and described in detail, it will be evident to those skilled in the art that modifications may be made without departing from the invention as defined in the appended 25 claims.

30 I claim:

1. Apparatus of the character described comprising a pair of similarly shaped sections having sloping bottoms, vertical risers and sloping tops having a portion thereof, extending at an angle from the remainder thereof and means for spacing said sections whereby the bottoms thereof overlap each other.

2. Apparatus of the character described comprising a pair of similarly shaped, oppositely disposed sections having overlapping bottoms and having angularly extending top edges whereby a relatively large space is afforded between said top edges.

3. Apparatus of the character described comprising a pair of similarly shaped, oppositely disposed sections having sloping overlapping bottoms, means for supporting said sections at the point of overlap, means for supporting the outer edges of the bot-

35 toms thereof and means for spacing said sections apart.

4. Apparatus of the character described comprising a pair of similarly shaped oppositely disposed sections having overlapping bottoms and so shaped as to constitute a hollow form having a relatively large central opening at the top thereof, whereby said sections may be removed from concrete 55 poured and hardened therearound, a plurality of substantially horizontal rods on each side of said central opening and having upstanding ends adapted to be bent over the opening left in the concrete by the removal of said sections, a flat form adapted to close said opening and to prevent poured concrete from 60 entering the void formed by said sections and means for securing said flat form to said bent over rods.

5. The method of molding hollow concrete 70 flooring which comprises setting up a pair of forms having overlapping bottom edges and top edges spaced apart, pouring concrete around said forms to a height approximately 75 level with the top edges of said forms, simultaneously imbedding in said concrete on each side of said forms, a plurality of substantially horizontal rods having upstanding ends, permitting said concrete to harden, removing said forms through the opening in the concrete provided by the spaced top edges 80 of the form, lowering a flat form into the void so formed, bending the upstanding ends of said rods across the opening in the concrete, securing said flat form to said rods, pouring concrete into said opening and onto said flat 85 form and finishing the flooring.

6. Apparatus of the character described comprising a plurality of forms having sloping bottoms, vertical risers, sloping tops composed of overlapping sections one of which 90 has a portion extending at an angle from the remainder thereof and means for spacing said forms whereby the bottoms thereof overlap each other.

In testimony whereof, I have signed my name to this specification.

WILLIAM KLEITZ.
